UNITED STATES PATENT OFFICE.

GEORGE P. BLANCHARD, OF ATHENS, GEORGIA.

SPECTACLES.

978,982.

Specification of Letters Patent. Patented Dec. 20, 1910.

Application filed November 22, 1909. Serial No. 529,390.

To all whom it may concern:

Be it known that I, GEORGE P. BLANCHARD, a citizen of the United States, residing at Athens, in the county of Clarke and State of Georgia, have invented certain new and useful Improvements in Spectacles, of which the following is a specification.

This invention has relation to certain new and useful improvements in spectacles.

10 The object of my invention is to provide a simply constructed, readily operated device, whereby spectacle lenses may be securely fastened within their frames, without the use of screws, in a manner permitting the lens or temple being readily replaced, without the use of tools.

With the above and other objects in view, the present invention consists in the combination and arrangement of parts as will be hereinafter more fully described and particularly pointed out in the appended claim, it being understood that changes in the specific structure shown and described may be made within the scope of the claim 25 without departing from the spirit of the invention.

In the drawings forming a portion of this specification, and in which like numerals of reference indicate similar parts in the several views, Figure 1 shows a front elevational view of a lens holder constructed according to my invention, Fig. 2 is a section on the line 2—2 of Fig. 1, Fig. 3 shows an enlarged detached detail of the 30 latch as used in my invention, Fig. 4 shows a fragmentary portion disclosing the lower ear in top view, Fig. 5 is a top view of the joint, Fig. 6 is a perspective view of the upper ear, Fig. 7 shows a detached detail 35 of the temple, Fig. 8 shows an inner edge view of the lower ear disclosing the closed position of the latch, Fig. 9 shows a bottom view of the upper ear, Fig. 10 shows the temple and connected pin.

40 As has been set forth, the aim of my invention is to provide a neat looking and substantial lens frame so constructed that the lens frame can be sprung apart permitting the ready removal of the lens or temples.

45 In the accompanying drawings, the numeral 5 designates a lens frame; the numeral 6 the upper, and the numeral 7 the lower pin ear. The lower pin ear has a 50 flat upper and a flat lower surface and is carried upon the pin 20 arranged to work

within the aperture 9 within the upper ear 6. The upper ear 6 is offset so as to provide the lower socket 10, while within the upper face of this ear is located the latch 66 socket 11 as clearly disclosed in Fig. 6. Within this lower socket is formed the circular shoulder 13 and the stop shoulder 12 as disclosed in Fig. 9 where I show an under-view of the upper ear. 65

The temple 15 as employed in my invention has the eye or enlargement 16 provided with the aperture 17 and the extending stop ear 18, this ear being arranged to work against the stop shoulder 12 within the lower 70 socket of the upper ear. The stop ear 18 limits the movement of the temple in one direction.

The pin 20 as used in my invention is of one diameter as shown in Fig. 10. In this 75 view the temple is shown upon the pin in section. The pin 20 is held in the head 28 of a latch to be described and is engaged through the lower ear, the temple and the upper ear in the order named, for the retention of these parts in operative relation, the temple being pivotally movable between the 80 ears.

Carried upon the pin 20 is a latch including the head 28 secured upon the lower end 85 of the pin and the upwardly extending portion 29 which is provided with the shield or latch 30 extending inwardly in spaced relation with the head 28 and arranged to snugly fit into the socket 11 within the upper ear 6. 90 In Fig. 1, I disclose a front view of the latch in closed position. The pin 20 is riveted within the lower portion 28 of the latch.

From the foregoing description, it will be seen that I provide a lens frame with an 95 upper and a lower ear, that the lower ear is held upon a pin which pivotally supports the temple and that the pin is riveted to a latch, and that the latch is arranged to clasp over the upper ear to securely fasten the two 100 ears together.

The operation of inserting a lens is very simple. The latch being swung outwardly, the frame is spread by separating the ears 6 and 7, the temple being retained upon the 105 pin 20, after which the lens is properly introduced within the frame. The upper ear 6 is then forced down over the pin 20 and upon the lower ear securely retaining the temple therebetween. The latch shield 30 is 110 then swung inwardly and over the upper ear 6 into the socket 11, where the latch is se-

curely held in frictional engagement with the upper ear. After forcing the latch out of the socket, the lens and temple can of course be removed, and a new lens or temple

5 replaced in an instant.

What is claimed is:

A spectacle comprising a lens frame, ears forming the terminal meeting ends of same, the upper ear being offset to form a latch 10 socket above the same, a temple the ear of which is confined between the ears of the lens frame, a latch having a lower ear, a pin carried by the latter, said pin freely passing through said ears of the lens frame

and ear of the temple, the latch having a 15 free engaging end, and an inwardly extending shield forming a part of the engaging end of said latch and adapted to be snugly received by the latch socket adjacent to the lens frame and out of contact with the pin 20 when the parts are properly brought together.

In testimony whereof I affix my signature, in presence of two witnesses:

GEORGE P. BLANCHARD.

Witnesses:

PUELA ELDER,
E. B. HUDSON.
